UNITED STATES PATENT OFFICE.

WILLIAM CHALMERS, OF LOVELOCKS, NEVADA.

MATCH STRIKE.

Application filed September 21, 1921. Serial No. 502,203.

To all whom it may concern:

Be it known that I, WILLIAM CHALMERS, a citizen of the United States, and a resident of Lovelocks, in the county of Pershing and State of Nevada, have invented certain new and useful Improvements in Match Strikes, of which the following is a specification.

The present invention relates to an improvement in match-strokes especially adapted for use with smoking pipes.

The object of the invention is to provide a device of this character which is especially adapted for use on the ordinary five-cent corn cob pipe and which, while comparatively inexpensive to produce, affords a ready, convenient and effective means for the ignition or lighting of matches and enhances the appearance and utility of the pipe.

Other objects and advantages of the invention reside in certain novel features of construction, combination and arrangement of parts which will be hereinafter more fully described and particularly pointed out in the appended claim, reference being had to the accompanying drawing forming part of this specification, and in which:

The figure is a fragmentary perspective

view of the invention embodied in a smoking pipe. 30

Referring to the drawing, the numeral 20 designates an ordinary corn cob pipe having a bowl 21 provided with a flat bottom to the under surface of which a disk 22 is 35 attached by means of an adhesive such as glue or the like or by other fastening means. The exposed face of the disk is surfaced to provide a match strike. The same effect may be had by applying glue or the like 40 to the pipe bottom and then dipping it into sand.

The latter method of producing the match scratch on the flat bottom on the bowl is preferred since it is comparatively inexpensive and is susceptible of embodiment in the ordinary five-cent corn cob pipes so as to provide the users of such pipes the convenience of a match scratcher and also to enhance the appearance and general utilities 50 of the pipe.

I claim:

In a match scratcher, a pipe having a bowl with a flat bottom, and an abrasive material directly cemented onto the under 55 surface of said bottom.

WILLIAM CHALMERS.
